Master Lock Company

Filed May 8, 1972, Ser. No. 251,579

Term of patent 14 years

Int. Cl. D8—07

U.S. Cl. D8—137

FIG. -1

FIG. -2

FIG. -3

FIG. -4

FIG. 1 is an end and face perspective view of a hasp staple showing the design;

FIG. 2 is a bottom view thereof;

FIG. 3 is a side view of the hasp staple; and

FIG. 4 is an end view thereof.

The characteristic feature of my design resides in the flattened appearance of the staple legs in combination with a base, all as shown.

I claim:

The ornamental design for a hasp staple, as shown and described.
